P. KEMPTER

SANITARY CAN CONSTRUCTION

Filed Feb. 20, 1925

INVENTOR
Philip Kempter
BY ^{his} Clifford & Dunn
ATTORNEY

UNITED STATES PATENT OFFICE.

PHILIP KEMPTER, OF MILWAUKEE, WISCONSIN.

SANITARY-CAN CONSTRUCTION.

Application filed February 20, 1925. Serial No. 10,479.

To all whom it may concern:

Be it known that I, PHILIP KEMPTER, a citizen of the United States, residing at Milwaukee, in the county of Milwaukee and State of Wisconsin, have invented new and useful Improvements in Sanitary-Can Construction, of which the following is a specification.

This invention relates to improvements in sanitary can construction.

In the metallic containers in present day use, a material defect, that of weakness of the head or collar portion, is readily observable. Further, considerable trouble is experienced in placing the cap for the container in proper closing and sealing position within the head portion due to the distortion of the collar portion adjacent the cap seating portion of the head. To remedy this difficulty, wire strands have been soldered to the collar portion adjacent the head, but such reinforcing means have merely served as temporary stiffeners, whose function was destroyed within a short time, due to the rough handling to which these containers are subjected.

Among the objects of the present invention it is contemplated to provide a reinforced upper portion in a container; to provide a structurally simplified and yet rigid head and collar portion on said container; to provide a novel structural arrangement of the head portion in a fluid container whereby to insure a perfect leak-proof fit of the cover within the head portion adjacent the collar portion; to eliminate the use of additional reinforcing means positioned along the collar portion and used in conjunction with the head of the container; and to form a container of stamped or seamed metal at a relatively lower production cost and simpler in structural detail from those heretofore in use, but possessing sufficient rigidity to withstand the rigor of constant rough handling.

Specifically, it is aimed in this invention to alter the entire structural formation of the upper section of the container, whereby to eliminate the usual one piece collar and head portion with its accompanying reinforcing wires or bands and to provide in lieu thereof a separate head portion of greater rigidity than the collar portion and adapted to be permanently fastened thereto.

Further, it is aimed to provide a reinforcing backing which is permanently fixed to

the collar portion and serves as the head portion of the container.

Further, it is aimed to provide a recess in the head portion, which recess serves to insure a perfect seal-retention means for the cap or covering for the container in order to prevent leakage from the top thereof.

Still further, it is contemplated to form the head portion of a metal stamping of thicker material than that of the collar portion, so as to form a firm cap retaining seat and at the same time form a proper reinforcing medium for the upper portion of the container.

Still further, it is aimed to provide a single bead, band or wire at the rolled top portion of the head to form the head reinforcing means for the container.

Still further, it is aimed to so construct the rolled wall of the head as to provide a resilient cap retaining recess in the head of the container.

These and other advantages, capabilities and features of the invention will appear from the subjoined detailed description of but one specific embodiment in which my invention may take form, which embodiment is illustrated in the accompanying drawing, in which—

Fig. 1 is a front elevation of the section containing the subject-matter of the invention; and

Fig. 2 is a section along lines 2—2 of Fig. 1.

Referring now more particularly to the reference characters of the drawing, in which but one of the possible embodiments of my invention is illustrated, numeral 1 represents a container, formed in this case by the well known metal manufacturing process. Numeral 2 represents the collar portion of one type of container contemplated in my invention, which collar portion, as shown in the drawing is illustrated as extending vertically upward and integral with the body portion 100 of the container, though the slope thereof may be readily varied. This collar portion, it will be observed, is of the same thickness as the body portion and consequently presents a weakened area at the upper surface 105 thereof.

The head portion 3, which is adapted to be fastened to the upper section of the collar 2 by welding, brazing, soldering, or any other way of attaching, consists of an annular

stamping having an offset flange 4 adapted to fit about the periphery of the collar 2; a cap receiving base 5 bent angularly over the flange; and a circular reinforcement receiving ring formed by bending the metal angularly with respect to the base and having an end extremity out-turned against the outer wall of the container to form a ring so as to allow a heavy reinforcement to be 10 inserted therein.

As shown clearly in Fig. 2, the head portion 3 is considerably thicker than the collar portion 2, so that the offset flange portion 4, when secured to the collar portion by any 15 of the above-mentioned methods, will form a backing and reinforcing means of much greater rigidity and strength than the walls of the collar portion.

The cap receiving base 5 which is formed 20 at right angles to the offset flange portion 4 which connects the head 3, of which it is a part, to the collar 2 of the container has a recess 9 formed at its outer periphery. This recess can be formed in the manufacturing 25 process by bending the wall 8 forming the wire receiving groove 6 to form an angle less than a right angle as illustrated in Fig. 2. By means of this particular inclination of the wall 8, the recess 9, which is formed 30 between this wall and the base 5, will assure a perfect seat for the cap (not shown), which cap, when inserted, will be prevented from being displaced upwardly by abutting the resilient angularly inclined wall 8.

35 The cap, whether it be a plain paper disc, or a paper disc backed by metal, or a paper disc metal edged, or the common metallic cover, is pressed down into the angular recess against the resistance of the wall 8 and 40 is maintained therein in perfect sealing relation by the pressure of the inwardly inclined wall 8.

45 By means of this separable head portion, attached to the collar portion of the container in any of the above-mentioned methods, it can be readily seen that a simple structure, having a minimum of reinforcing bands and wires and having considerable 50 rigidity throughout the whole area of contact of the flange 4 with the collar portion, will produce an ideal container. Further, though the particular inclined formation 55 of the wall of the reinforcement receiving groove may be readily changed so as to produce more or less enlarged recesses, the recess will always serve as a definite sealing medium, since the upper part of the inclined wall will always contact with the collar por-

tion of the well-known metallic cover or cap, or contact with the outer periphery of the 60 disc of paper or the metal reenforced paper disc serving as a cover for the container.

While the preferred embodiment of the invention has been described with great detail, it is to be understood that this is for 65 the sake of clearness only, and does not limit the scope of the invention as described by the annexed claims.

What is claimed is:

1. In a container, the combination with 70 a collar portion, of an annular head fastened to said collar portion, said head having a base portion, an offset flange portion and an oppositely offset wire receiving portion at the outer periphery of the base, said flange portion being fastened to the collar portion, and said wire receiving portion being extended angularly upwardly and inwardly from said base to form a recess at the outer periphery of said base.

2. In a container, the combination with 75 a body portion, of a head portion attached thereto, a base on said head portion, an upwardly and inwardly extending wall integral with said base, said upwardly extending wall forming a recess with the base for the retention of a cover cap on said base, and a downwardly extending wall on said base forming the attaching means.

3. In a container, the combination with 80 a collar portion, of an annular head portion attached thereto, said head having a base portion, said base having angular flanges extending in opposite directions at the inner and outer peripheries thereof, one of said 85 flange portions being fastened to the collar portion to form a reinforcing backing therefor and the other flange portion being extended angularly upwardly and inwardly to form a cap retaining recess between itself and the base portion.

4. In a container, the combination with 90 a body portion, of a head portion attached thereto, a base on said head portion, an inwardly and upwardly extending wall integral with said base, said upwardly extending wall forming a recess with the base for the retention of a cover cap on said base, and a downwardly extending wall on said 95 base forming the attaching means, said downwardly extending wall being of thicker material than said body portion whereby to form a reinforcing backing therefor at the point of attachment.

PHILIP KEMPTER.
